UNITED STATES PATENT OFFICE.

THOMAS L. RICHARDSON, OF EDINBURG, INDIANA.

TONGUE FOR PLOWS, MOWERS, &c.

SPECIFICATION forming part of Letters Patent No. 245,865, dated August 16, 1881.

Application filed June 11, 1881. (No model.)

To all whom it may concern:

Be it known that I, THOMAS L. RICHARDSON, a citizen of the United States, residing at Edinburg, in the county of Johnson and State of Indiana, have invented a new and Improved Jointed Tongue for Sulky-Plows, Mowers, and other Agricultural Implements, of which the following is a specification.

With draft-tongues of common construction 10 the turning of the plow or mower, as at the end of a furrow or swath, has to be accomplished by pulling the horses to one side, when the side pressure of their shoulders on the neck-yoke and front end of the tongue drags 15 the machine around—a slow and laborious operation.

My invention relates to means whereby the turning of the machine can be accomplished by a direct forward pull of the horses on the 20 traces.

In the accompanying drawings, Figure 1 is a perspective view of the jointed tongue as applied to a sulky-plow. Fig. 2 is a vertical longitudinal section of the joint.

The tongue is formed of two parts, A and B, of which A is fastened by the usual means 25 to the hounds or frame of the machine, while the part B is pivoted to the forward end of the part A by bolt C. A semicircular metallic 30 disk or frame, E, is fastened to the rear end of the pivoted tongue B, either by flanges projecting from it and screwed to the tongue, as shown, or otherwise. To the rear part, A, of the tongue is screwed or otherwise attached 35 a plate, F, a flange, f, of which extends over the curved portion of the semicircular disk, and is pierced at f', for the reception of a spring or other stop, G, a shoulder, g, of which, when the stop is in its elevated position, enters a notch, e, in the semicircular disk and 40 prevents the turning of the disk and the tongue B. When, however, the stop is pressed down, as by the driver's foot, the shoulder is removed from the notch and the disk and tongue are 45 free to turn, the side movement being stopped by shoulders e' of the disk.

In operation, the tongue being in its straight

or normal position, it will be held in such position by the catch G to the end of the furrow or swath being run. When, however, it is 50 desired to turn the machine, as to make a cross-furrow, the driver, pressing down with his foot on catch G, releases it from the notch in the disk, and by pulling the horses they are turned around until the shoulders e' of the 55 disk strike on the plate F, or as far short of that as he may desire, according to the angle to be turned. The catch G, being held retracted by the shoulder g, slides under the edge of the disk. Then, starting the horses up, the two 60 parts of the tongue are swung once more into line by the draft of the traces, the catch springs back to its place, and the new furrow or swath is made. By repeating this operation the machine can be doubled on itself, and a return 65 furrow made without any side strain on the tongue or horses.

The flanged plate F not only serves as a guide to the segmental disk E, but by bearing on the upper face of said disk prevents 70 the swagging of the tongue when turned from its support on the end of the stationary portion A.

In a sulky-plow the double-tree D is preferably connected directly to the beam H. In a 75 mower the double-tree is attached by the joint-bolt C, or by a separate bolt or clevis on the rear member of the tongue, as preferred.

Having thus described my invention, the following is what I claim as new therein and 80 desire to secure by Letters Patent:

1. The combination, with segmental disk E and tongue B, of the stationary guide-plate F, projecting over said disk and preventing 85 swagging of the tongue, as set forth.

2. In combination with the divided tongue A, B, the plate F, having flange f, segmental disk or frame E, having notch e and shoulders e', and stop or catch G, all substantially as and for the purpose set forth.

THOS. L. RICHARDSON.

Witnesses:

MADISON LORD,
WM. F. HAMILTON.
